Primary Examiner — Kelley A Donnelly(74) *Attorney, Agent, or Firm* — Andrus Intellectual Property Law, LLP(57) **CLAIM**

We claim the ornamental design for shelf components, as shown and described.

DESCRIPTION

FIG. 1 is a perspective view of shelf components showing our new design; and,
FIG. 2 is a top view thereof.

The dot-dash broken lines are boundary lines, which form no part of the claimed design. The shelf components shown in broken lines in the figures depict unclaimed environmental subject matter and form no part of the claimed design. Similarly, unshaded portions that appear beyond boundary lines in the figures form no part of the claimed design.
